LIGHTING FIXTURE

Clifford V. Bates, Chicago, Ill.

Application April 3, 1944, Serial No. 529,243

2 Claims. (Cl. 240—41)

My invention relates to improvements in lighting fixtures.

One object of the invention is to provide an improved fixture in which the incandescent lamp may be renewed without disfiguring or tarnishing the polished surface of the reflector by contact with the fingers.

Another object is to provide a sealed in unit of generally improved and simplified construction.

In the accompanying drawing I have illustrated two embodiments of the invention.

Fig. 1 is a rear elevation of one form of lighting fixture;

Fig. 2 is a side view partly in section and partly in elevation;

Fig. 3 is a view looking through the open rear door of the cylindrical casing along the longitudinal axis;

Fig. 4 is a side elevation of the lamp base and associated parts;

Fig. 5 is an end view of the lamp base;

Fig. 6 is a sectional elevation of a modification.

The lighting fixture illustrated in Figs. 1-3 of the drawing was designed more particularly for use as a berth light for a triple-deck sleeping car for troops, although capable of many other uses. Said fixtures are mounted in pairs against a side wall of a sleeping car, and preferably are spaced apart one above each of the two windows of a section and in general direct the light rays diagonally downward and somewhat converging, some of which rays from the two sources intersect each other.

The lighting fixture housing 10 is shown as being cylindrical in form with a rear closure or door 11 hinged thereto at 12 and comprising a mounting plate for the fixture. Said plate has slots 13 therein, each enlarged at one end to permit ready mounting thereof by means of screws 13', or other suitable fastening devices. An additional small opening 14 is provided, as well as a larger central opening 15, through which the conductors enter from the lighting circuit. The locking device 16 is provided to hold the door shut, it being understood that said door is mounted in fixed position, as for example, against the vertical side wall of the sleeping car, whereas the container may be swung out from the side wall to give access to the rear thereof. Said base, which is oval in shape, is arranged in a plane at an acute angle with respect to the longitudinal axis of the cylindrical container, and is tilted somewhat as shown in Fig. 1.

The body may be locked to the base by a screw 17 having a knurled head. The outer end of the container is provided with a flanged cap or re-

taining ring 18, preferably welded to the cylindrical side wall. It carries a plurality of small bolts 19 with nuts 20 having the form of elongated strips of metal which overlie the rim of the reflector 21 and hold the same in position. A gasket 22 of suitable material such as cork, for example, engages the rim of said reflector and is engaged by the convex glass member 23 which has inner intersecting ribs thereon to diffuse the light in the conventional manner. This glass panel is confined beneath a flange or bezel comprising part of the retaining ring 18. With this arrangement the fixture comprises a sealed in structure at least insofar as the compartment between the glass panel and the reflector is concerned, the highly polished surface of the reflector being inaccessible either from the front or the rear. In assembling the fixture said reflector is inserted from the rear as will be evident.

20 The reflector has a central opening which receives a base or cylindrical socket 24 for a suitable lamp 25, or source of light. The cylindrical socket and the lamp may be handled as a unit and inserted part way through said opening from the rear. Said socket 24 has a flange 26 which engages the rear of the reflector and limits the insertion, and said socket is provided also with a plurality of spring fingers 27 shown in Figs. 4 and 5, which permit the same to snap into the opening and resist withdrawal therefrom.

To withdraw the base and the lamp carried thereby when, for example, it is necessary to replace the lamp, the operator swings the base in any direction to rock it about some point of contact of the flange 26 with said reflector. Fig. 4 shows in dotted lines the normal position of the base of the lamp, whereas the full line position shows the unit swung upwardly to disengage the spring fingers sufficiently to enable the base and the lamp to be pulled completely out of the opening. In reassembling the structure the reverse manipulation is followed, i. e. the lamp is inserted through the opening somewhat diagonally and then the base is swung into position with the flange 26 engaging the rim of the opening in the reflector. To effect this renewal of the lamp it will be understood, of course, that the housing is swung outwardly from the supporting cover so as to make the interior accessible from the rear, somewhat as shown in Fig. 3. This method of renewal eliminates any risk of contact between the fingers of the operator and the polished surface of the reflector. Not only do finger marks disfigure the surface, but in time will result in tarnishing.

As shown also in Fig. 3 the conductor 28 from the lamp socket leads to the switch structure 29 whereby the circuit may be opened and closed by moving the conventional switch arm 30. The other conductor 31 leading from the switch extends out through the opening 15 in the rear plate to the supply circuit and another conductor 32 therefrom is grounded at one of the clips 20. The conductors 31 and 32 are of ample length to permit the main housing to be swung away from the cover when renewing the lamp. When the lighting fixture is in normal position the housing is closed and locked and the device as a whole comprises a sealed in unit.

Fig. 6 shows a modified structure intended as an overhead fixture, although not necessarily limited to any particular position.

The mounting plate or base 35 has a housing 36 hinged to it at 37 and provided with a locking screw 38. A switch 39 is mounted in the wall of the housing with conductors connected in the same general manner as illustrated in Fig. 3, to the incandescent lamp 40 which is carried by the socket 41, the latter being removably mounted in an opening in the reflector 42. The details of construction of the socket 41 may be the same as that illustrated in Figs. 4 and 5. The transparent closure for the lower end of the lighting fixture is shown at 43, the circular end being preferably of clear glass and the cylindrical portion being frosted or otherwise translucent.

The surface of the reflector in this case also is inaccessible, the lamp being removed to the rear through the opening in the reflector when the housing is swung downwardly about its hinge. This form of the device also is a sealed in construction.

Although the fixture shown in Fig. 5 is shown on a somewhat smaller scale than the one shown in Fig. 3, it will be understood that these may not only be of the same diameter but many of the parts may be interchangeable. For example, the retaining ring 18 may be formed in the same die which is used to form the housing 36. The gaskets, reflectors and retaining clips may be identical in the two cases. The convex lens shown in Fig. 2 may be used also in the device of Fig. 6, and vice versa.

Various other changes, rearrangement of parts and changes in detailed construction may be made without departing from the spirit of the invention as expressed in the appended claims.

I claim as my invention:

1. A lighting fixture comprising a housing having an inwardly directed flange at the front end thereof forming a bezel, a transparent panel disposed adjacent said bezel and forming a closure for the front of said housing, a reflector positioned adjacent said transparent panel, means interlocking with said housing and engaging said reflector to maintain said reflector

and said transparent panel in position against said bezel to form a sealed unit in the front end of said housing, said reflector being provided with an opening in the rear portion thereof, a lamp socket insertable from the rear into said opening and provided with spring clips for engagement with the edge of said reflector at said opening to maintain detachably said socket in operative position in said reflector, a supporting plate forming a closure for the rear of said housing, a hinged connection between said supporting plate and said housing, and means for mounting said supporting plate to a wall whereby said housing may be swung open on its supporting plate to permit access to the rear of said reflector and to permit disengagement of said socket from said reflector for the insertion of a lamp bulb in said socket without damaging the reflecting surface of said reflector.

2. A lighting fixture comprising a housing in the form of a substantially cylindrical sheet metal member and having an inwardly directed flange at the front end thereof forming a bezel, a transparent panel disposed adjacent said bezel and forming a closure for the front of said housing, a reflector having a flange positioned adjacent the periphery of said transparent panel, means interlocking with said housing and engaging the flange of said reflector to maintain said reflector and said transparent panel in position against said bezel, to form a sealed unit in the front end of said housing, said reflector being provided with an opening in the rear portion thereof, a lamp socket assembly including a lamp insertable from the rear into said opening and provided with a flange to limit its forward motion and with spring clips which engage the edge of said reflector at said opening to maintain detachably said socket in a predetermined axial position with respect to said reflector, a switch mounted in the interior of said housing and having an actuating arm extending outwardly through an opening in said housing, a supporting plate forming a closure for the rear of said housing, a hinged connection between said supporting plate and said housing, the rear end of said housing being shaped so that the longitudinal axis of said cylindrical member is inclined with respect to said supporting plate whereby said reflector and its associated parts are hingedly supported on an inclined axis, means for mounting said supporting plate to a wall, an opening in said supporting plate, and a flexible conductor extending from the interior of said housing through said opening in said supporting plate to provide means for connecting said lamp to a supply line, said conductor being of sufficient length to permit the opening of said housing when it is desired to detach said socket for lamp changing purposes.
